UNITED STATES PATENT OFFICE.

IRA ORVILLE WRIGHT, OF BALTIMORE, MARYLAND.

DRAFT-YOKE.

1,203,834.

Specification of Letters Patent.

Patented Nov. 7, 1916.

Application filed December 19, 1912. Serial No. 737,621.

To all whom it may concern:

Be it known that I, IRA ORVILLE WRIGHT, a citizen of the United States of America, residing in the city of Baltimore, State of Maryland, have invented certain new and useful Improvements in Draft-Yokes, of which the following is a specification.

This invention relates to a yoke for railway draft gears, and particularly to a two-part yoke consisting of a jaw member and a loop.

The jaw member is slotted to receive one or two keys and the loop may be connected to the jaw member by any suitable means. Preferably the loop is pivoted to swing laterally relatively to the jaw member.

In the preferred form of the invention, the jaw member is made with a longitudinal opening to permit the draw-bar to pass therethrough and engage the followers within the loop. As shown, this opening is of sufficient size to admit the yoke, and the jaw member is slotted rearwardly from the front at the top and bottom, the slots terminating in sockets or seats which receive corresponding studs on the ends of the loop.

In setting up the device, the loop is inserted from the front into the opening in the jaw member, the studs on the ends of the arms of the loop entering the slots, and as the loop is moved to the rear, they become seated in the sockets at the ends of the slots. The longitudinal opening in the jaw member is of sufficient width to permit the loop to swing through a considerable arc. Thus the connection between the draw-bar and the tension member or loop is given a sufficient degree of flexibility to eliminate all danger of breaking due to lateral motion of the draw-bar in winding bends, etc. Further, the jaw member and loop are detachably connected, and may be easily and conveniently separated so that either part can be quickly replaced in case of break-down.

The accompanying drawings illustrate a draft yoke constructed in accordance with my invention.

Figure 1 is a vertical, central section through the yoke, certain parts being shown in elevation. Fig. 2 is a view half in plan and half in central, horizontal section. Figs. 3 and 4 are, respectively, an elevation and a plan of the loop member. Fig. 5 is a vertical section showing a second form of my invention.

Referring to the drawings by numerals, each of which is applied to the same element in the different figures of the drawing,—in the preferred form of the invention, as shown, the yoke consists of a jaw member 1 and a loop or tension member 2. The loop is of U-shape, the arms 3 being provided at their forward ends, one with a stud 4 projecting upward and the other with a depending stud 5. The jaw member has a longitudinal aperture at 6 to admit the rear end of the draw-bar and also of sufficient size in a vertical direction to admit the loop exclusive of the studs 4 and 5. To receive and coöperate with the studs, the jaw member is slotted at 7, the slots being open at the front and extending rearwardly, preferably tapering as shown, and provided at their rear ends with seats or sockets 8, shown as arcuate in form, the radius of the arc being slightly greater than the radius of the studs 4 and 5.

Thus, in setting up the draft gear, the rear end of the loop is inserted in the jaw member from the front, the studs 4 and 5 entering the slots 7, and the loop is passed to the rear to the position shown in Fig. 1 until the studs are seated in the sockets or seats 8. Thus the loop and jaw member are pivotally connected, forming a flexible yoke, the aperture in the jaw member being of sufficient lateral dimension to permit the loop to swing laterally through a considerable arc. Within the yoke the usual shock-absorbing means not shown is mounted.

The jaw member shown in Figs. 1 and 2 is slotted at 9 to receive a horizontal key which passes through a corresponding slot in the draw-bar 14. This key may be seated in safety slots in the sills after the usual manner or otherwise arranged, and the jaw member is of sufficient length to receive a second key 10 mounted in rear slots 11 therein. This key coöperates with the sills and the shock-absorbing means in the usual or any suitable manner. In Fig. 5 I have shown a similar yoke which is cut away on the line 12 inclosing the slot 11. The yoke as thus formed is adapted to be used with the single-key type of draft gear, as well as with the two or three key gear.

It will be easily understood that the draft yoke thus described has all the advantages of the cast steel yoke with a vertical loop and the horizontal key connection. At the same time the jaw member, which is the only

portion of the yoke which under the present practice is best made of cast steel, is of such dimensions that the amount of cast steel required is comparatively slight, where-
5 by the cost of manufacture of the yoke and likewise its weight are reduced. At the same time, the loop may be conveniently made of wrought iron or soft steel.

The draft yoke described has other im-
10 portant advantages in that it is flexible later-
ally so that no side stress which can be ap-
plied will break it. Also the loop and jaws
are conveniently detachable, so that either
15 may be removed and interchanged in case
of breakdown without considerable delay.

I have thus described specifically a single embodiment of my invention in order that its nature and operation may be clearly understood. However, the specific terms here-
20 in are used in their descriptive rather than in their limiting sense and the scope of the invention is defined in the claims:

1. In a device of the class described, a draw-bar and a yoke strap, a hollow head
25 embracing both elements and provided with

an extending fork, and means penetrating said fork and adapted to unite the parts of the device together.

2. A yoke for draft gears consisting of a jaw member and a loop, the jaw member 30 having a horizontal aperture to receive the front key and a second horizontal aperture to receive a rear or intermediate key.

3. In combination in a draft rigging for cars, a vertical yoke having pivot members 35 at the front ends and a hollow jaw member through which the arms of the yoke extend, the jaw member being adapted to receive the end of the M. C. B. draw bar and having sockets for the pivots of the yoke, slots in 40 alignment with the slot in the draw bar and elongated slots in the rear of said first mentioned slots.

Signed by me at Baltimore, Maryland,
this 18th day of December, 1912.

IRA ORVILLE WRIGHT.
